UNITED STATES PATENT OFFICE.

JOHN T. MEATS AND WILLIAM ASHWORTH, OF TAUNTON, MASSACHUSETTS,
ASSIGNORS TO THE MASON MACHINE WORKS, OF SAME PLACE.

DESIGN FOR A LIFTING-ROLL HOLDER FOR TEXTILE MACHINERY.

SPECIFICATION forming part of Design No. 31,865, dated November 21, 1899.

Application filed October 18, 1899. Serial No. 734,023. Term of patent 14 years.

To all whom it may concern:

Be it known that we, JOHN T. MEATS and WILLIAM ASHWORTH, citizens of the United States, residing at Taunton, county of Bristol, 5 and State of Massachusetts, have invented and produced a certain new and original Design for a Lifting-Roll Holder for Textile Machinery, of which the following is a specification, reference being had to the accompanying drawings, forming a part thereof.

Figure 1 is a front perspective view of a lifting-roll holder for textile machinery, illustrating our design; and Fig. 2 is a similar but rear view thereof.

15 The leading feature of our design for a lifting-roll holder for textile machinery consists in a substantially T-shaped body having its transverse top or head notched at its upper edge and with fingers projecting from the front of the head, said fingers having inclined recesses in their extremities.

The lifting-roll holder has a substantially T-shaped body, the transverse top or head A

having a series of notches a in its upper edge, and the stem A' , depending from the head, being bent up at the front side of the body at A^2 . Fingers a' project from the front of the head, and at their extremities the fingers are provided with rearwardly-inclined open recesses a^2 , giving to the fingers the appearance of 30 hooked ends.

Having fully described our design, what we claim, and desire to secure by Letters Patent, is—

The design for a lifting-roll holder for textile machinery, substantially as shown and described.

In testimony whereof we have signed our names to this specification in the presence of two subscribing witnesses.

JOHN T. MEATS.
WILLIAM ASHWORTH.
